J. R. COE,
APPARATUS FOR ROLLING METAL.
APPLICATION FILED JUNE 12, 1920.

Patented Sept. 12, 1922.

2 SHEETS—SHEET 2.

UNITED STATES PATENT OFFICE.

JAMES ROBERT COE, OF WATERBURY, CONNECTICUT, ASSIGNOR TO THE AMERICAN BRASS COMPANY, OF WATERBURY, CONNECTICUT, A CORPORATION OF CONNECTICUT.

APPARATUS FOR ROLLING METAL.

Application filed June 12, 1920. Serial No. 388,423.

To all whom it may concern:

Be it known that I, JAMES R. COE, a citizen of the United States, residing at Waterbury, county of New Haven, State of Connecticut, have invented a certain new and useful Improvement in Apparatus for Rolling Metal, of which the following is a full, clear, and exact description.

My invention relates to improvements in apparatus for rolling metal and has for its object to provide an apparatus in which rolls of comparatively small diameter can be safely and effectively employed.

Heretofore in rolling metal the apparatus necessary has been very large and heavy, rolls of some twenty-four inches in diameter being used for what is known as the breaking down of the bars, and rolls of comparatively large diameter being used for the subsequent rollings. These rolls of large diameter have been found to be necessary on account of the great stresses to which they are subjected. The trunnions and bearings for these rolls are all of a correspondingly large size requiring large bearings and introducing great friction. One of the stresses which these rolls are required to resist is the stress which tends to result in their bending apart, and more or less of such bending is found to be present even with rolls of large diameter, since they are supported only at their ends, while the metal between them bears against their central portions. Another reason for using such large rolls is that it is necessary to have the adjacent surfaces on two such rolls in ordinary rolling apparatus approach each other quite gradually, since if the rolls are so small as to cause the surfaces to approach more or less abruptly, they will not bite the end of the metal so as to draw it in between them. One of the objections to the large rolls with the gradually approaching surfaces is that when the metal is drawn in between them it is subjected to a swedging or rending action as distinguished from a squeezing action, which swedging or rending action extends for a considerable distance and distorts the fibers much more than a more localized compressing action would do.

In my improved rolling apparatus these objections are largely avoided and the re-

sult is shown in the product, in which the metal appears to be more compressed and of quite different texture than the product produced by the ordinary large power-driven rolls.

A further object of my invention is to provide a new and improved means for permitting the metal to be inserted between the rolls and subsequently compressing it to the desired degree. A further object of my invention is to provide an apparatus in which a product is formed which varies in thickness, the two faces being symmetrical to a central plane. A further object of my invention is to provide means for producing a rolled product which shall be accurately tapered from one end to the other or of any desired irregular cross-section.

The following is a description of an embodiment of my invention, reference being had to the accompanying drawings, in which,

Fig. 1 shows a side elevation of my apparatus with a bar of metal about to be acted upon;

Fig. 2 shows a similar view in which the action upon the bar of metal is nearly completed;

Fig. 3 shows details of a rack member of my apparatus;

Fig. 4 shows in side elevation a track member of my apparatus;

Fig. 5 shows in plan view a detail of one of my rolls and connections therefrom;

Fig. 6 is a side elevation of the same;

Fig. 7 is an end elevation of the apparatus showing the bar to be acted upon in section on the line 7—7, Fig. 1;

Fig. 8 shows diagrammatically another means for causing the bar to pass between the rolls;

Fig. 9 shows still another such means;

Fig. 10 shows diagrammatically a modification of the apparatus of Fig. 1, whereby the extreme forward end of the bar, as well as all other parts of the bar, can be reduced to a uniform thickness;

Fig. 11 shows a bar being reduced in thickness at its forward end by the apparatus of Fig. 10;

Fig. 12 shows a subsequent step in which the remainder of the bar is being reduced to the desired thickness by that apparatus;

Fig. 13 shows an arrangement in which the resultant product is tapered uniformly from one end to the other;

Fig. 14 shows such product, and

5 Fig. 15 shows an arrangement for periodically increasing and decreasing the thickness of the bar throughout its length.

Referring more particularly to the drawings, 1 is an abutment and 2 is a bed, which 10 two elements are relatively movable. Thus, the abutment 1 may be the head of a planer of which 2 is the traveling bed. Secured to the bed 2 is a massive framework consisting of top and bottom members 3, 4, which are 15 secured together by side plates 5 bolted thereto. In longitudinal recesses contained in the top and bottom members are U-shaped members 6 and 7 secured in place, the opposing faces of the legs of the U having 20 teeth 8 so as to constitute racks. In the central recesses in these U-shaped members are two relatively fixed tracks 9 and 10 secured in place. Within the casing thus described are two juxtaposed rollers 11 and 12, having 25 complete cylindrical rolling surfaces which travel along the tracks 9 and 10, these tracks being in line with the bodies of the rollers and engaged thereby so as to resist any outward thrust to which the rollers may 30 be subjected when a bar of metal 13 is passed between them. Upon the reduced trunnions of these rollers are rigidly secured pinions 14, 14 and 15, 15, which engage the teeth 8 of the rack members 6, 7, the pitch lines 35 being substantially in line with the laterally extending surfaces of the tracks 9 and 10 respectively. The rack faces of the portions 6 and 7 and also the face of the track 9 are curved at one end, as shown at 16 and 40 17 of Figs. 3 and 4 and also in Fig. 2 so as to produce a gradually opening mouth at the starting or entrance end of the frame. The trunnions of the rollers 11 and 12 are extended beyond the pinions 14 and 15, and on 45 these extensions are links 18, 18 and 19, 19, in whose rear ends the rollers are journaled and whose forward ends are movably connected to the abutment 1. Springs 20 located between opposing links of the two bars 50 tend to separate the two pairs and hold the upper and lower gears 14 and 15 out of engagement with one another and in engagement with their respective tracks. In actuating the machine the forward end of 55 a bar 13 is presented to the rolls 11 and 12, when they are at the mouth of the framework. The rolls are then moved relatively to the framework and along the tracks 9, 10, which, as they approach one another, 60 cause the rolls to press upon the bar 13 so as to reduce its thickness. This movement can be caused by positively moving the abutment 1, the framework being held stationary, or by positively moving the 65 framework, the abutment being held station-

ary, or it can be caused by a direct pull upon the bar by a draw head 21, as shown in Fig. 8, or a direct push by a hydraulic ram 21' as shown in Fig. 9. In the construction shown in Fig. 1, the tracks 9, 10 and the racks 6, 7 are parallel except at the mouth of the framework, so that the bar except at its extreme front end is reduced to a uniform thickness, and the links 18 and 19 hold the plane passing through the axes 75 of the rollers at right angles to the medial line between the tracks. The faces of the tracks are symmetrical to this medial plane.

In order to reduce the front end of the bar to a similar thickness, I extend the 80 framework to the right beyond the mouth of the apparatus shown in Fig. 1, and bring the faces of the tracks and racks in this extended portion into line with the faces of the main portions thereof as shown in Fig. 85 10. With this arrangement the bar is inserted between the rolls when the rolls are at the enlarged portions 16, as shown in Fig. 10, and then the rolls are first moved toward the right, whereupon the portions 22 of the 90 track cause the rolls to approach one another and reduce the thickness of the end of the bar to the desired extent, as shown in Fig. 11. After this preliminary reduction has taken place, the rolls are restored to the position 95 shown in Fig. 10 and moved to the left, whereupon they engage the bar so as to reduce the thickness of the remaining portion thereof as the rolls are moved to the left, as shown in Fig. 12. 100

By my invention a uniformly tapered product may be produced. In order to accomplish this end I locate the tracks so that their ends 23 are nearer together than the points 24. With this arrangement, when the 105 bar is inserted as shown in Fig. 10 and made to move toward the left, the rolls compress it more and more, producing the tapered product shown in Fig. 14, the front end of the bar being the thicker and both sides of 110 the bar being symmetrical with relation to a central plane.

If it is desired to form a bar with symmetrically located undulating sides I provide the tracks with undulations such as 115 valleys 25 and crests 26, the valleys and crests being located opposite to each other respectively, as shown in Fig. 15. When the bar is passed between rolls engaging tracks of this construction, the product has 120 undulating sides which are symmetrical to a central plane. In all instances racks having their pitch lines substantially in line with the faces of the tracks at all points, such as shown in Figs. 1 to 4, are employed. 125

With this construction the tracks resist the stresses due to the action of the rolls upon the bar so that the rolls can be made of comparatively small size. On account of this reduction in size, the amount of sur- 130

- face of the roll contacting with the metal is small so that the swedging or rending action of the rolls upon the metal is largely reduced, the action being more of a compressing action. The difficulty of inserting the metal between small rolls is avoided by the flaring of the tracks at the starting point so that the objects of my invention are attained.
- 10 As will be evident to those skilled in the art, my invention permits of various modifications without departing from the spirit thereof or the scope of the appended claims.
- What I claim is:
- 15 1. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, and means for maintaining the plane passing through the axes of said rollers substantially at a right angle to a plane medial to said tracks.
- 20 2. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, and means for maintaining the plane passing through the axes of said rollers substantially at a right angle to a plane medial to said tracks, said tracks and racks adjacent to the starting ends thereof being separated more than at other points.
- 25 3. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, and means for maintaining the plane passing through the axes of said rollers substantially at a right angle to a plane medial to said tracks, and longitudinally moving means for causing said rolls to move along said track members.
- 30 4. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, and two pairs of links connecting said rollers and said abutment and holding said rollers in said plane at right angles to a plane medial to said tracks.
- 35 5. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, two pairs of links connecting said rollers and said abutment and holding said rollers in said plane at right angles to a plane medial to said tracks, and means tending to separate the ends of the pairs of links connected to said rollers.
- 40 6. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, means for maintaining the plane passing through the axes of said rollers substantially at a right angle to a plane medial to said tracks, and longitudinally moving means for causing said rolls to move along said track members.
- 45 7. In an apparatus for rolling metal strips, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, two pairs of links connecting said rollers and said abutment and holding said rollers in said plane at right angles to a plane medial to said tracks, and longitudinally moving means for causing said rolls to move along said track members.
- 50 8. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, two pairs of links connecting said rollers and said abutment and holding said rollers in said plane at right angles to a plane medial to said tracks, and longitudinally moving means for causing said rolls to move along said track members.
- 55 9. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, two pairs of links connecting said rollers and said abutment and holding said rollers in said plane at right angles to a plane medial to said tracks, and longitudinally moving means for causing said rolls to move along said track members.
- 60 10. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, two pairs of links connecting said rollers and said abutment and holding said rollers in said plane at right angles to a plane medial to said tracks, and longitudinally moving means for causing said rolls to move along said track members.
- 65 11. In an apparatus for rolling metal, the combination of two juxtaposed rollers having rolling surfaces completely surrounding their body portions, two relatively fixed tracks having opposing faces, said tracks engaging the body portions of said rollers so as to contact with said rolling surfaces, gears upon the ends of said rollers, racks fixed relatively to said tracks and with which said gears engage, the pitch lines of said gears being approximately in line with the faces of said tracks, an abutment as to which said tracks are relatively movable, two pairs of links connecting said rollers and said abutment and holding said rollers in said plane at right angles to a plane medial to said tracks, and longitudinally moving means for causing said rolls to move along said track members.

in said plane at right angles to a plane medial to said tracks, and means for causing relatively longitudinal movement between said tracks and said abutment.

- 5 8. In an apparatus for rolling metal strips, the combination of two juxtaposed rollers having rolling surfaces completely surrounding their body portions, two relatively fixed tracks having opposing faces, 10 said tracks engaging the body portions of said rollers so as to contact with said rolling surfaces, gears upon the ends of said rollers, racks fixed relatively to said tracks and with which said gears engage, the pitch 15 lines of said gears being approximately in line with the faces of said tracks, and means for maintaining the plane passing through the axes of said rollers substantially at a right angle to a plane medial to said tracks, 20 the distance between said tracks varying, their opposing faces being symmetrical to said medial plane.

9. In an apparatus for rolling metal strips, the combination of two juxtaposed rollers 25 having rolling surfaces completely surrounding their body portions, two relatively fixed tracks having opposing faces, said tracks engaging the body portions of said rollers so as to contact with said rolling 30 surfaces, gears upon the ends of said rollers, racks fixed relatively to said tracks and with which said gears engage, the pitch lines of said gears being approximately in

line with the faces of said tracks, and means for maintaining the plane passing through the axes of said rollers substantially at a right angle to a plane medial to said tracks, the distance between said tracks being gradually smaller as the finishing ends of said tracks are approached so that the space 40 between said tracks tapers.

10. An apparatus for rolling metal having, in combination, a pair of rollers relatively movable toward and from each other to receive the metal between them, abutment 45 members engaging the metal engaging portions of the peripheral surfaces of the rollers to limit the movement of the rollers away from each other during the operation thereof on the metal, and means for positively rotating the rollers in a direction to feed the metal between them.

11. An apparatus for rolling metal having, in combination, a pair of rollers relatively movable toward and from each other 55 to receive the metal between them, tracks engaging the metal engaging portions of the peripheral surfaces of the rollers to limit the movement of the rollers away from each other, and means for relatively moving the tracks and rollers in a direction longitudinally of the tracks, and for positively rotating the rollers in a direction to feed the metal between them, during said relative movement of the rollers and tracks. 60 65

JAMES ROBERT COE.
